APPARATUS FOR SPRAYING HAT BODIES

Burling D. Wells, Danbury, Conn., assignor to
 The Mallory Hat Company, Danbury, Conn., a
 corporation of Connecticut

Application March 2, 1940, Serial No. 321,829

17 Claims. (Cl. 223—7)

This invention relates to a method and apparatus for spraying hat bodies particularly for preparation of the hat bodies for being subjected to a subsequent operation.

One of the objects of this invention is to provide a dependable and practical apparatus, of efficient action, for conditioning hat bodies for being subjected to a subsequent operation in the course of manufacture. Another object is to provide a simple and reliable apparatus spraying onto hat bodies liquid or like solutions or compositions. Another object is to provide a method and apparatus for dependably and inexpensively preparing hat bodies for luring.

Another object is to carry out the above-mentioned objects in a thoroughly practical and efficient way for operation upon hat bodies conformed to have the shape of a crown and brim and where not only the crown but also both sides of the brim are to be prepared for a subsequent operation, such as luring. Another object is to provide an apparatus for carrying on such operations as are above noted with a minimum of manual supervision and at a high production rate. Another object is to provide an apparatus for automatically carrying on the application to the surface or surfaces of a hat body of liquid or other preparations, particularly by way of preparation for subsequent operations on the hat body, such as luring.

Another object is to provide a method and apparatus for spraying liquid or other preparation onto the surface or surfaces of hat bodies that will be capable of ready and convenient adaptation to meet varying conditions met with in practice. Other objects will be in part obvious or in part pointed out hereinafter.

The invention accordingly consists in the features of construction, combinations of elements, arrangements of parts and in the several steps and relation and order of each of the same to one or more of the others, all as will be illustratively described herein, and the scope of the application of which will be indicated in the following claims.

In the accompanying drawings in which is shown by way of illustration one of the various possible embodiments of the mechanical features of my invention,

Figure 1 is a plan view with certain parts in section, other parts broken away, and other parts indicated diagrammatically;

Figure 1^a is a schematic or diagrammatic view showing several of the various positions of traverse of one of the parts relative to the hot body; 55

Figure 1^b is a detached partially schematic showing of a clutch mechanism and its actuating means;

Figure 2 is a front elevation, certain parts being broken away, other parts being shown in central vertical section and other parts being indicated diagrammatically;

Figure 3 is an elevation as seen from the rear in Figure 1;

Figure 4 is a circuit diagram of heater elements and their controls.

Similar reference characters refer to similar parts throughout the several views of the drawings.

In order better to illustrate certain of the various features of my invention, let it be assumed that the hat body, generally indicated in the drawings by the reference character 10, is at that stage of its manufacture where it is about to be lured and where it has already been given a shape to provide it with a crown C and a brim B, the outer surface of the crown and both faces, usually referred to as the upper brim and under brim, of the brim are to be prepared for the subsequent operation, such as luring. Preferably the hat body is mounted upon a block 11 which is received within the crown C which snugly conforms to the shape and contour of the block and by way of the block 11 I support the hot body for rotation preferably about a horizontal axis, as is better shown in Figures 2 and 3.

Such support I may achieve in any suitable way as, for example, by means of a shaft 12 having a bearing support in a suitable frame 13 with suitable driving connections to rotate the shaft 12 at a suitable and preferably relatively low speed, say a speed on the order of 45 R. P. M.

In view of certain other features of my invention, I preferably employ an electric motor 14 suitably geared to the shaft 12 to drive the latter and I preferably embody the motor and the gear drive into or with the frame 13 so as to form a compact sub-assembly or sub-unit. Shaft 12 preferably has a substantial overhang from the frame 13 and at its outer end is provided with any suitable form of chuck construction, such as that indicated generally at 15, for detachably grasping and holding the block 11 with the axis of the hat body, usually oval, substantially coincident with the axis of shaft 12. The jaws 16 of the chuck may be controlled in any suitable way as by the clamping collar 17, link 18, and spring biased lever 19, so that removal and replacement of the blocked hat body may be con-

veniently and readily achieved, without having to interrupt the drive of the chuck shaft 12.

In the preferred form, I preferably effect relative movement, at appropriate intervals, between the hat-holding chuck and the device or devices that are to operate upon the hat body and in carrying out this preferred arrangement I preferably provide a suitable number, illustratively eight, sub-units, like those above-described, each for holding a blocked hat body, and mount them upon a movable carrier arranged to move them successively into and out of operative relation to the other apparatus. Such a carrier may comprise a bed 20 (Figures 1 and 2) suitably supported for rotation at its center and the hat-supporting units I mount on the bed 20 adjacent its periphery, arranging them so that their chucks are equidistant from the axis of bed rotation and so that the axes of the hat-carrying shafts 12 lie in vertical planes through equiangularly spaced radii of the bed 20.

Suitable means are provided for effecting step-by-step rotary movement of the bed 20 and such means may comprise any suitable or appropriate mechanism and in Figure 2 I have indicated the rotary support for the bed 20 and the mechanism for effecting step-by-step rotary advance or movement thereof only diagrammatically, as at 21, the drive of this mechanism being preferably by means of an electric motor 22.

The step-by-step driving mechanism 21 may be of any suitable or desired form or type of mechanism and illustratively it may comprise a Geneva stop movement, various forms of which are well known. Where the rotary bed 20 carries, as in the above-mentioned illustration, eight hat-supporting devices, the driving mechanism 21 is constructed to give the bed 20 successive rotary movements each of 45° extent and with a suitable time interval interposed between successive increments of movement. During such time intervals during which the hat bodies are at rest, operations upon the latter may proceed according to the kind or types of operating machines related to the respective stations, and of these machines one may, for example, be a luring machine and the one at the preceding station is a machine for preparing the surfaces of the hat body for the luring operation.

Such a machine may comprise a suitable main base or frame 25 (Figures 1, 2 and 3) having suitable pillars 26, 27 for supporting suitable bearings 28, 29 that rotatably support a shaft 30 from which preferably the various mechanisms and controls are operated. Shaft 30 is driven at a suitable rate of speed, preferably relatively low, by any suitable means, preferably by an electric motor 31 (Figure 2) suitably supported in an upstanding frame part 32, the latter preferably housing and supporting part of the driving connection between the motor and the shaft 30.

Thus, frame part 32 rotatably supports a shaft 33 (Figure 2) whose left-hand end is in geared connection, as at 34, with the shaft of motor 31 and whose right-hand end carries, exposed in the frame part 32, a worm 35 which meshes and coacts with a worm wheel 36 mounted coaxially with the shaft 30 by way of a hub 37 which at one end (see Figure 1) is formed to provide, or has attached to it, a toothed clutch part 38 with which coacts a companion toothed clutch part 39 which is also carried by shaft 30 but is splined thereto as at 40 so that clutch part 39 may be moved axially along shaft 30 while maintaining a driving connection therewith.

Clutch 38-39 is preferably constructed and controlled, in an illustrative manner later described, to effect a drive of driven clutch part 39 and hence of shaft 30 throughout a rotary movement of a certain extent, illustratively and preferably an extent of one complete revolution and hence 360°, whence the movable clutch part 39 is disengaged from the driving clutch part 38 to halt the drive of shaft 30. Subsequent shifting of clutch part 39 into engagement with clutch part 38 is preferably effected in timed relation to the rotary step-by-step movements of the rotary bed 20, in an illustrative and preferred manner as later described.

As above pointed out, it is preferably from the shaft 30 that various mechanisms and controls are operated; these mechanisms preferably comprise means, preferably in the form of spray nozzles or spray guns for applying to the exposed surfaces of the hat body 10 a suitable medium to prepare the hat body for the subsequent luring operation. As appears in the drawings, the parts are preferably so related to each other that during the interval of stoppage of the bed 20 a hat body, carried and rotated by a shaft 12, becomes positioned so that its axis and that of the shaft 12 is substantially in alignment with the longitudinal axis of the frame 25, with the rotating hat body overhanging one end of the frame, and preferably the spray guns are two in number, being generally indicated by the reference characters 41 and 42, and as better appears in Figure 2 they are preferably arranged in such spaced relation that they are on the respective sides of the plane of the brim B of the hat body.

Spray gun 41 is preferably mounted in good thermal relation to a tank or container 43 (see Figure 2) which is to contain the luring preparation indicated at 44 in Figure 2, and since the latter preferably comprises components that include grease-like materials, it is preferred to maintain the preparation 44 at a suitably high temperature, thereby also to control or fix its viscosity at a point where it flows freely enough for proper handling by the spray gun 41 which, as later noted, is preferably constructed to function in the manner of an atomizer. Accordingly, I prefer to construct the tank 43 of a material of good thermal capacity, such as aluminum, giving it preferably suitably heavy or thick walls. Suitable heating means are also provided and that may take the form of an electric heating unit 45 preferably accommodated in a suitable recess in the tank 43, under the control preferably of a thermostatic switch 46 also appropriately related thermally to the tank and its contents as, for example, by housing it in a suitable recess, as indicated in Figure 2.

The spray gun 41 is preferably mounted for movement relative to the rotating hat body to vary the direction of its discharge and to effect application of the luring preparation to the different parts of the crown and preferably also to the upper brim. A preferred mechanism for effecting such movement may comprise a carrier arm 47 whose right-hand end (see Figure 2) has a downwardly extending shank externally cylindrical to provide a shaft-like support for the carrier arm 47, as shown at 48, the shaft part 48 being supported for rotary movement about a vertical axis in a bearing formed in an upstanding boss 50 adjacent the right-hand end of frame 25. At its left-hand end the carrier arm 47 is shaped to provide an upwardly directed stud-like shaft 51 with which is rotatably interfitted a sleeve-like

lug extension 52 of the tank 43, that extension having a laterally projecting arm 53 for a purpose later described.

At the lower end of the shaft part 48 of the carrier 47 is a pinion 54 (Figures 2 and 3) with which meshes the rack portion of a rack bar 55 which is preferably square in cross-section and which is mounted for sliding movement longitudinally of the frame 25 by way of suitable bearings 56, 57. Near the left-hand end of rack bar 55, as seen in Figure 2, the bar has secured to it an upstanding arm 58 carrying in its forked end a roller 60 which coacts as a cam follower with a cam 61 secured to the main shaft 30. Suitable means, such as a spring 62 (Figure 2) maintains engagement of the cam follower 60 with the cam 61. Cam 61 is given a suitable contour or shape, illustratively as indicated in Figure 2, so that, when shaft 30 and hence cam 61 are rotated in counter-clockwise direction (Figure 2) rack bar 55 is shifted to give the pinion 54 and hence the spray gun and tank carrier 47 rotary movements of the desired extents, rates and directions, as is later described.

Such swinging of the carrier 47 about the axis of the bearing 50, the latter axis being preferably positioned so as to intersect the axis of rotation of the hat body 10, preferably adjacent the plane of the brim (compare Figures 1 and 2), is preferably also accompanied by a change or shifting of the direction of the axis of the spray or discharge emanating from the mouth or nozzle end 41a of the spray gun 41. Such a change or shift I preferably achieve by changing the angular relationship between the tank 43 and the carrier arm 47 and may be effected by means of a link 63 pivotally connected at one end to the arm 53 of the tank 43 and connected at its other end as by a ball and socket 64 or other universal type of connection to one end of a lever 65 whose lower end is pivoted as by pin 66 in a suitable bracket or eye of the frame 25 (Figure 2).

Lever 65 carries a roller 67 to coact as a cam follower with a cam 68 mounted on the main shaft 30, a spring 70, connected between lever 65 and a stationary part of the frame 25, holding the cam follower 67 always in engagement with the peripheral cam face of the cam 68. As the latter thus rotates, it effects shifting of the lever 65 in a manner not only to compensate for the motion of translation (in a yoke) of the axis of the tank-supporting stud shaft 51, but also determines the extent and rate of shift or change of the tank 43 and spray gun 41 angularly with respect to a fixed axis or plane, such as the longitudinal axis of the frame 25 or a vertical plane passing through such an axis.

To effect ejection of the luring preparation from the tank 44, preferably in the form of a spray of fine particles of the preparation, I prefer to bring into action air under pressure, and depending upon the character of the luring preparation, being preferably of the kind earlier above noted, I preheat the air under pressure that takes part in effecting discharge of the preparation onto the hat body.

Thus, referring again to Figure 2, I may provide a suitable source of supply of air under suitable pressure, such as a tank and pump, as is diagrammatically indicated at 71 and lead air by suitable piping or conduit 72 and 73, preferably after preheating it in a suitable heater 74 which may be in the form of an electrical heating unit of suitable construction, to the movably mounted tank 43 and spray gun or nozzle 41,

preferably utilizing a suitable length of flexible conduit, as indicated at 75 in Figure 2.

By way of conduit 76, preferably with a pressure-regulating valve 77 interposed therein, air under suitable pressure is fed into the tank 43 in the space above the level of the luring preparation 44, the pressure of the air being maintained substantially constant by the action of the regulating valve 77 which is of any suitable or appropriate construction and preferably also adjustable, as indicated in Figure 2, thus maintaining the luring preparation 44 under suitable pressure and thereby insure its flow upwardly through a pipe or conduit 78 to the spray gun 41, the lower end of the pipe 78 being exposed near the bottom of the tank 43 and being preferably provided with a strainer 80.

By way of conduit or piping 81 with preferably a pressure-regulating valve 82 interposed therein, air under pressure is fed directly to the spray gun 41 at a suitable pressure maintained substantially uniform by the pressure-regulating valve 82 which also is of any suitable construction and preferably adjustable, as indicated.

The spray gun 41 may be of any suitable internal construction, having preferably a suitable means, such as a hand wheel or thumb screw 83 for adjusting its action and being also preferably provided with suitable valve means diagrammatically indicated at 84 in Figure 2, for starting and stopping its action. This valve means 84 is preferably controlled in a timed relation to the action or movement of other parts of the apparatus, as is described below in greater detail, and the mechanism for controlling the valve means 84 may comprise a bell crank lever 85 pivotally related to the gun 41 and having connection with the valve means 84 so that the latter assumes open or closed or intermediate positions according to the position given the bell crank lever 85 about its pivotal support.

Lever 85 extends toward the nozzle end of the gun 41 and to one side thereof, where, at its end, it is connected to a link 86 that extends downwardly adjacent the right-hand end face of the tank 43, as seen in Figure 2 (see also Figure 3), and at its lower end link 86 is pivotally connected to a plunger-like rod 87 which is mounted and guided for vertical sliding movement in the upright shaft extension 51 of the carrier arm 47, the part 51 being for that purpose hollow or sleeve-like to provide an internal cylindrical bearing surface for the plunger rod 87 that is concentric with the external bearing surface of the part 51 and about which the tank 43 itself may swing.

Extending about the upwardly exposed portion of the plunger rod 87 and interposed between the upper end of the shaft part 51 and a suitable abutment adjacent the upper end of the rod 87 is a helical spring 88 under the expansive force of which rod 87 is urged upwardly to move valve control lever 85 in a direction to shut off the valve means 84 and thus stop the discharge of the luring preparation onto the hat body.

The lower end of plunger rod 87 that projects below the carrier arm 47 is provided with an elongated slot or eye 90, preferably of adjustable effective length, as shown in Figure 2, in which is engaged one end of a lever 91 shaped as is better shown in Figures 2 and 3 to extend through a recess or slot 47a (see Figure 1) in the carrier arm 47 in which it is pivoted by pivot pin 92. The other or upper end of the lever 91, thus brought to the upper side of carrier 47, extends over the shaft-like part 48 which also is prefer-

ably sleeve-like in construction, being bored out or otherwise formed to provide a cylindrical bearing surface 48^a for slidably supporting a round plunger rod 93 coaxially with the axis of the shaft part 48 and with its upper end underneath the upper arm of lever 91.

The lower end of rod 93 engages one arm 94 of a bell crank lever pivotally supported in a shaft 95 carried by the frame 25 and whose other arm 96 extends upwardly through a suitable aperture in the top face of the frame 25 into cooperative relation to a cam 97 (Figure 2) on the main shaft 30, arm 96 carrying a roller at its end to function as a cam follower 98 in coaction with the peripheral cam surface of cam 97.

The weight of the plunger rod 93, coupled with the action of spring 88, suffices to maintain cam follower 98 in engagement with cam 97.

As cam 97 thus rotates when shaft 30 rotates, the valve means 84 of the spray gun 41 is shifted or positioned according to the shape of the cam 97.

The companion or coacting spray gun 42 (Figures 2 and 3) is in general of the same construction as the device 41 with its associated tank 43 and related parts. The gun 42 is again preferably mounted on a tank 100 having an electric heating unit 101 with a thermostatic control switch 102 therefor to maintain the luring preparation at the desired temperature and viscosity. The tank 100 with the gun 42 is secured as by bracket part 103 to one end of the frame 25, as by securing it to the boss 50 thereof, thus preferably positioning the gun 42 in alignment with but underneath the overhanging shaft 12 of the hat-supporting and rotating mechanism when the latter is positioned by bed 20 during a point of stoppage of the latter, the nozzle or discharge end 42^a of the gun 42 being directed toward the face of the under brim, the general relationship being as shown in the drawings.

By piping or conduit 105, with a pressure-regulating valve 106, also preferably adjustable, interposed therein, air under pressure, and also preferably heated, is led to the spray device 42 as by piping 107 with pressure-regulating valve 108, also preferably adjustable, interposed therein, air under pressure, and also preferably heated, is supplied to the tank 100 in the space above the luring preparation contained therein.

The spray gun 42 is also provided with suitable valve means, diagrammatically indicated at 110, like the valve means 84 above described, being controlled by a bell crank lever 111 whose operating arm extends downwardly alongside of the tank 100 (see Figure 3) where it is pivotally connected to a link 112 (see Figures 1 and 3) that extends lengthwise and above the frame 25 to a lever 113 to whose upper end it is pivotally connected and whose lower end is pivoted to a suitable fixed part of the frame 25 as at 114. Lever 113 carries a cam follower in the form of a roller 115 intermediate of its length for coaction with a cam 116 on cam shaft 30. A spring 117 (Figures 1 and 3), having one end connected to the valve-controlling bell crank lever 111 and having its other end anchored to the tank 100, urges the lever 111 in a direction to close the valve means 110 and also in a direction always to maintain the cam roller 115 in engagement with the periphery of cam 116.

Accordingly, with motor 31 continuously driving clutch member 38 and with each motor 14 driving, also preferably continuously, its associated chuck shaft 12 with a blocked hat held

in the chuck 15, the presentation of a blocked hat like the hat 10 to the spraying mechanism, effected by the actuation of the bed 20 through the step-by-step mechanism 21, preferably with 5 interlocking controls and coactions as are later described in greater detail, the various parts of the spraying apparatus are in substantially the positions shown in the drawings, being virtually the starting positions; with the completion of 10 the proper positioning of the rotating hat body 10, clutch member 39 (Figure 1) is actuated to bring about its engagement with the driving clutch member 38, thus to initiate the drive of the main shaft 30 which thus commences to 15 rotate.

The actuation of clutch 38-39 is preferably achieved electromagnetically. Thus, referring to Figures 1 and 1^b, clutch member 39 may be axially shiftable by a lever 120 suitably provided 20 at its midpart with a yoke with which a trunnioned ring about the clutch member 38 is pivotally connected, lever 120 being pivoted at its left-hand end in a fulcrum block 121 slidably mounted in suitable guides formed in a bracket 25 122 secured to the side of the frame 25 and carrying an adjustable stop 123 between which and the fulcrum block 121 is interposed a spring 124 tending to press the block 121 away from the stop 123. Thus, upon actuating lever 120 in 30 clutch-engaging direction, spring 124 can yield and fulcrum block 121 slide away from the frame 25 should the teeth of the two clutch members not be properly related at the instant of lever actuation, lever 120 being held in actuated position by a latch 125 and spring 124 thereupon effecting clutch interengagement upon the necessary and small ensuing relative rotation between the clutch parts as may be necessary to mesh the toothed parts thereof.

Such actuation of clutch lever 120 also effects withdrawal of the end 127^a of a lock lever 127, pivoted upon a suitable fixed part and connected by link 128 to clutch lever 120, from a recess 39^a in the side face of clutch part 39, releasing it 45 for rotation. Clutch 38-39 is held in engaged position by the action of part 127^a of lock lever bearing against the side face of cam part 39. As the latter rotates, cam 126 on the clutch part 39 comes around and, prior to completion of the 50 single revolution of the clutch part 39, trips the latch 125 to permit subsequent movement of lever 120 to disengage the clutch parts.

Such tripping of latch 125 having taken place, clutch lever 120 swings in counter-clockwise direction under the urge of spring 144 to disengage the movable clutch part 39 from the driving clutch part 38 only when lock lever 127, connected to the clutch lever 120 by link 128, is permitted to swing in counter-clockwise direction by the entry of its left-hand end 127^a into the recess 39^a in the side face of the clutch part 39, thus disengaging the clutch at the end of a single revolution and thus locking the clutch part 39 and shaft 30 in a position of rest.

An electromagnet or solenoid comprising a winding 130 and a core 131 has the latter connected pivotally to an operating bar 132 which is biased by a spring 133 in a direction to cause a stud or end portion of lever 120 to be engaged within a notch 134 in the operating bar 132. Accordingly, energization of the winding 130 is effective to swing the lever 120 in clockwise direction to achieve clutch engagement in the manner above described.

Energization of winding 130 to effect clutch

actuation as above-described, I prefer to take place under control of or in dependence upon the rotary position of bed 20. Thus, the bed 20 may have a cylindrical periphery 20^a (Figure 1) provided with equidistantly spaced cam recesses 20^b which in number are the same as the number of hat-supporting and rotating devices carried by the bed 20, illustratively eight, and positioned to coact with the peripheral parts of the bed 20 is a switch structure 135 which has a cam part or follower 136 urged in a direction toward the cam periphery of the bed 20 by a spring 137, the switch structure being so positioned that its cam part 136 enters a cam recess 20^b only upon the completion of an increment of rotary movement of 45° (where there are eight hat-carrying devices on the bed 20) with resultant halting of one of the hat-carrying devices with a blocked hat thereon in proper relation to the tools 41 and 42, as above described. The bed 20 coming to a halt at such point thus effects actuation of the switch 135 to close an energizing circuit, like that shown in Figure 1, to the winding 130, thus to actuate the clutch 39—38 and commence the drive of the main shaft 30 throughout one complete revolution.

With the commencement of drive of the shaft 30 in counter-clockwise direction, as viewed in Figure 2, the coaction between cam 61 and cam follower 60 commences a rotary movement of the carrier arm 47 and at the same time cam 97 moves bell crank lever 96—94 in a direction to shift valve lever 86 in counter-clockwise direction (Figure 2) to move the valve means 84 into open position, thus commencing the emission from the mouth or nozzle end 41^a of the spray gun 41 of a substantially cone-shaped spray of heated luring preparation in finely divided or atomized form, the axis of the cone-shaped spray being at the outset substantially coincident with the axis of rotation of the hat body 10 so that the top part of the rotating crown (the left-hand part as seen in Figure 2) has the preparation uniformly deposited on it.

In this connection, it will be noted that the spray gun is also maintained at a suitably high temperature, obtaining heat not only from the heated tank 43, by conduction and otherwise, but also from the flow of heated luring liquid and from the flow thereto of heated air. Also, the emission from the nozzle end 41^a of both heated finely divided luring preparation and of heated air insures against condensation in transit across the air space between the nozzle end and the hat body and insures dependable deposit of the material onto the hat body itself, together with the transfer of some heat to the hat body as well.

In Figure 1^a this initial position of the spray gun 41 is diagrammatically indicated at A.

Under control of cam 61 arm 47 swings in counter-clockwise direction, as viewed in Figure 1, and during an earlier stage of that movement cam 68 (Figure 2) through the cam follower 67 and link 63 effects such a shift or control of the spray gun 41 and its support, about the axis of the stud shaft part 51, as to maintain it substantially parallel to its initial or starting position throughout a first portion of its arcuate traverse as effected by the carrier arm 47, thus to effect application of the luring preparation throughout the somewhat flat top part of the crown C, all during the continued rotation of the hat body; depending upon the shape of the cam, such a first or initial stage may extend through-

out the portion B of the otherwise substantially arcuate path of traverse of the mouth of the nozzle 41^a which, it will be noted, is substantially coincident with a vertical extension of the axis of the shaft part 51 about which the tank 43 may swing relative to the carrier 47. Thereupon, as, for example, throughout substantially the rest of the arcuate path or traverse indicated at C in Figure 1^a, cam 68 effects a progressive or continued change in the angle or direction of the axis of the cone-shaped spray discharge, the nozzle 41 assuming at the end of this portion C of the traverse a position somewhat as indicated at E in Figure 1^a, having, during its traverse, continued to discharge the luring preparation onto the rotating crown and applied the material substantially uniformly over the "square" of the crown and also over the side of the crown.

At the end of the portion C of the traverse (Figure 1^a), cam 61 (Figure 2) permits carrier arm 47 to pause or rest and during that pause portions of cam 68 come into effect to shift the spray gun 41 relative to the supporting shaft part 51 but in a direction to change the spray gun, preferably progressively, from the position E in Figure 1^a to the position F in which the cone-like discharge becomes directed onto the upper face of the brim B to the plane of which the axis of the gun and cone-shaped spray is now substantially at right angles, this position being held for a sufficient length of time to insure the deposit on the upper brim face of a sufficient quantity of the finely divided luring preparation.

During all of the above cam 97 through its connecting links and mechanism maintains the valve means 84 of the spray gun 41 open and, if desired, the shape of the portion of the cam effective during this interval may be varied if it is desired to vary the rate of emission of the gun as may sometimes be desirable according to the shape of the hat, such, as for example, the radius of curvature at the "square" of the hat crown.

While spray gun 41 has thus been operating upon the crown and upper brim of the rotating hat body, the companion spray gun 42 (Figures 2 and 3) is made effective upon the under face of the brim B. Under the control of cam 116 (Figure 3) which commences its rotation with the starting of the main shaft 30 and the other cams just above-mentioned, the valve means 110 of the spray gun 42 is actuated into position to effect a similar discharge of heated luring preparation, together with heated air, and, as shown in the drawings, spray gun 42 may, for these actions, remain stationary with its axis and hence the axis of its cone-shaped spray-like discharge substantially at right angles to the plane of the brim B.

According to the shape of the cam 116, valve means 110 may be actuated to start the spray discharge at any suitable point during the time interval of action of the spray gun 41. Thus, the under brim may be sprayed continuously during the spraying of the crown and upper brim, in which case, since the area to be covered is less in the former case than in the latter, the rate of emission by gun 42 is correspondingly less either by adjustment of the gun itself or by the shape of cam 116 or in any other suitable way. Or, the cam 116 may initiate the action of spray gun 42 only at about the time that spray gun 41 becomes effective upon the upper face of the brim B as when it reaches the position F

of Figure 1^a, whence the rates of discharge of the two guns may be substantially the same.

Thus, the exposed surfaces of the hat body may be dependably and uniformly sprayed with the luring preparation, it being pointed out, furthermore, that the spread of the cone-shaped spray from both nozzles is sufficient to deposit the sprayed preparation on all exposed parts of the hat body even though the latter may be, as is indicated in Figure 1^a, and usually is, oval in cross-section both as to crown and brim.

In a preferred mode of operation, the continued rotation of the above-mentioned cams may now effect, by cams 97 and 116 a closure of the valve means 84 and 110, respectively, of the two spray guns 41 and 42, and by way of cams 61 and 68 effective, during the remainder of the 360° rotary movement of shaft 30, a restoration of the movable spray gun 41 with its tank 43 to its initial or starting position and conveniently this latter movement may be caused by having the cams effect what may be a retracing of the traverse or successive positions above described in connection with, and shown in, Figure 1^a. It will be understood, of course, that, by suitably shaping the various cams, these actions may be otherwise interrelated, if so desired, and, for example, spraying may continue during both strokes of traverse so that cut-off takes place only upon return to starting position of the spray gun 41, though, in such case the rate of emission of the gun may be and preferably is cut down.

Just prior to completion by the main or cam shaft 30 of its rotary movement of 360°, a cam 140 on the shaft 30 momentarily actuates a cam follower 141 to tilt the operating bar 132 (Figure 1^b) in clockwise direction to disengage the lug end of lever 120 out of the notch 134, the continued energization of the winding 130 moving the operating bar 132 downwardly, further compressing a spring 143 against which the core 131 of the solenoid operates. The clutch lever 120 is thus freed from its engagement with the operating bar 132 and the latter is by the above actions also prepared for a subsequent actuation.

Upon the substantial completion, or somewhat prior thereto, of the 360° rotary movement of shaft 30, cam 126 trips the latch 125 to disengage it from the lever 120 and upon completion of the 360° rotary movement part 127^a of the lock lever 127 enters the recess 39^a in the clutch face 39, thus permitting spring 144 to move clutch lever 120 in counter-clockwise direction to disengage the movable clutch member 39 from the driving clutch member 38, thus bringing the shaft 30 to a halt.

Connected to be actuated concurrently with the halting of the shaft 30 is a switch 145 conveniently connected mechanically to the lock lever 127 so that, when the latter is actuated as just described to enter its lock part 127^a in the clutch recess 39^a, switch 145 is actuated in one direction, such as into closed position, to energize a circuit to initiate the actuation of the step-by-step mechanism 21 (Figure 2) and thus to start the rotary movement of bed 20 to move the sprayed hat out of the spraying apparatus and to bring into operative relation to the latter the next hat body to be operated upon.

For this purpose switch 145 may form part of a relay or control circuit comprising conductors 146 and 147 (Figures 1^b and 2) in which is included an electromagnet or solenoid 148 which when energized upon closure of switch

145 initiates the action of the Geneva stop movement or step-by-step mechanism 21, in any suitable manner. For example, between the mechanism and the motor 22 may be interposed a clutch 150 constructed in any suitable manner to be moved into engaged position upon energization of the solenoid 148; with the mechanism 21 now in action bed 20 partakes of movement throughout one step, such as 45°, moving the sprayed hat out of the apparatus and moving into operative relation to the apparatus a hat carried by the next succeeding hat-supporting and rotating frame 13 carried by the bed 20.

The rotary movement of bed 20 operates the switch mechanism 135 (Figure 1) thus to deenergize the winding 130 (Figures 1 and 1^b), permitting the solenoid core 131 and the operating bar 132 to move upwardly under the urge of spring 143 and thus reengaging clutch lever 120 in the notch 134 of the operating bar 132, thus preparing these parts for a subsequent energization of winding 130 and ensuing actuation of the clutch 38-39.

The step-by-step or Geneva stop mechanism 21, upon concluding the steps of moving and locking the bed 20, is preferably arranged to set the clutch 150 in disengaged position, as, for example, by means of a cam 151 which coacts with a cam follower, diagrammatically indicated at 152, arranged in any suitable way to actuate the clutch 150 into disengaged position at the proper moment and thus also prepare the clutch for a subsequent actuation in reverse direction by the solenoid 148. Upon bed 20 coming to rest switch 135 (Figure 1) is closed, thus energizing clutch control winding 130 which swings clutch lever 120 in clockwise direction (Figure 1^b) to initiate the cycle of action of the spraying tools on the newly positioned hat body; but the actuation of the clutch lever 120 actuates also switch 145, thus deenergizing the clutch control winding 148 (Figure 2) and preparing the latter for a subsequent energization when the hat-operating tools have completed their cycle of operations, as above described.

The bed 20, having, in the above illustration, eight hat-supporting and rotating means, may have at the corresponding eight stations thereabout suitable hat-operating mechanisms or machines aside from the spraying machine above described and at least one such other machine comprises a luring machine positioned at the station adjacent to the above described spraying machine so that the sprayed hat, as it is moved out of the spraying machine, is moved into operative relation to the luring machine to be lured; such a luring machine may take the form of that described in my co-pending application, Serial No. 321,828, filed of even date herewith and to that application reference may also be made for an embodiment in detailed form of the step-by-step mechanism 21 and its controls. Also, where the movable bed 20 is to coact with a sufficient number, such as eight, stations, and hence carries eight hat-supporting and rotating devices, I may also subdivide the eight stations into groups, each group comprising machines for performing successive and different operations on the hat bodies, such as spraying with a lure preparation at one station followed by luring at the next station, at least one station of each group being a loading and discharging station at which blocked hat bodies are replaced.

Thus, it will be seen that there has been provided in this invention a method and apparatus

in which the various objects heretofore noted, together with many thoroughly practical advantages, are successfully achieved. Uniformity of application of luring compound or preparation is efficiently achieved and thus also better uniformity of luring action and hence of ultimate polish of the fur felt or other material of the hat body insured. Also, it will be seen that the apparatus is of compact construction and thoroughly dependable in action and well adapted to meet the conditions of hard practical use.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

1. An apparatus for spraying a luring preparation onto the crown and the two sides of the brim of a hat body, comprising means for supporting and rotating a hat body about an axis at right angles to the general plane of the brim, two spraying devices having means supporting them in spaced relation on the respective sides of the plane of a brim of a hat supported in said supporting means, the supporting means for the spraying device on the crown side of said plane being movable, means for shifting said movable supporting means to traverse it and to change the angle of emission of its spraying device to effect spraying of the top, square, and side of the crown and the upper face of the brim, means for moving said hat-supporting and rotating means into and out of operative relation to said spraying devices, and means operating in timed relation thereto to effect traverse and shifting of said movable supporting means for said shiftable spraying device.

2. An apparatus as claimed in claim 1 in which said spraying devices are provided with control valve means, and means operating in timed relation to the movement of said hat-supporting and rotating means into and out of operative relation for controlling the emission of said two spraying devices.

3. An apparatus for spraying a luring preparation onto the crown and the two sides of the brim of a hat body, comprising means for supporting and rotating a hat body about an axis at right angles to the general plane of the brim, two spraying devices having means supporting them in spaced relation on the respective sides of the plane of a brim of a hat supported in said supporting means, the supporting means for the spraying device on the crown side of said plane being movable, means for shifting said movable supporting means to traverse it and to change the angle of emission of its spraying device to effect spraying of the top, square, and side of the crown and the upper face of the brim, and means for stopping the emission of both spraying devices upon conclusion of the traversing and shifting movement of said shiftable spraying device.

4. An apparatus for spraying a luring preparation onto the crown and the two sides of the brim of a hat body, comprising means for supporting and rotating a hat body about an axis at right angles to the general plane of the brim, a plurality of spraying means comprising spraying means positioned to one side of said plane for spraying the under side of a brim and spray-

ing means positioned to the other side of said plane and adapted to effect spraying of the crown and upper side of the brim, means for shifting said hat-supporting and rotating means to move a hat body carried thereby into operative relation to said spraying means and to move it out of operative relation therefrom upon the lapse of a certain time interval, and means for starting and then stopping the spraying action of said spraying means to effect spraying of the aforesaid surfaces of the hat body while the latter is rotating in operative relation thereto during said time interval.

5. An apparatus as claimed in claim 4 in which the spraying means operative upon the under side of the brim has a spread or cone of spray discharge of sufficient expanse to impinge upon the under side of the brim throughout its width and throughout such radial relative displacement of the rotating brim as is caused by whatever extent of oval shape that the brim might have, and means mounting said spraying means relative to said means for shifting said hat-supporting and rotating means to effect clearance therebetween and a hat body as the latter is shifted into or out of operative relation to said spraying means.

6. An apparatus as claimed in claim 4 in which the two spraying means have mounting means for effecting therebetween relative movement, and means operating in timed relation to the shifting means for said hat-supporting and rotating means to effect relative movement between said two spraying means.

7. An apparatus as claimed in claim 4 in which the spraying means operating upon the under side of the brim of the rotating hat body is stationary but has an effective spread of spray discharge of sufficient expanse to impinge upon the under side of the brim throughout its width and throughout such radial relative displacement of the rotating brim as is caused by whatever extent of oval shape that the brim might have and in which the other spraying means has means mounting it for movement, and means operating during the aforesaid time interval to effect movement of said movable spraying means to cause its discharge to impinge successively upon the crown and upper brim portions of the hat.

8. An apparatus for spraying a luring preparation onto a hat body, comprising means for supporting and rotating a hat body about an axis at right angles to the general plane of the brim, spraying means, means movably mounting said spraying means in operative relation to a hat body carried by said supporting and rotating means, said mounting means comprising a movable support with means mounting said spraying means thereon for movement relative to said support, cam means for effecting movement of said support to effect a traversing movement of said spraying means relative to said hat body, and cam means operative upon said spraying means to effect shifting thereof relative to said movable support.

9. An apparatus for spraying a luring preparation onto a hat body, comprising means for supporting and rotating a hat body about an axis at right angles to the general plane of the brim, spraying means, means movably mounting said spraying means in operative relation to a hat body carried by said supporting and rotating means, said mounting means comprising a movable support with means mounting said spraying means thereon for movement relative to said

support, means for effecting movement of said support to effect a traversing movement of said spraying means relative to said hat body, means operative upon said spraying means to effect shifting thereof relative to said movable support, said spraying means having valve control means, and means operating in timed relation to the movement of said spraying means relative to the hat body for controlling said valve control means.

10. A hat spraying apparatus comprising means for supporting a hat body, spraying means, means mounting said first-mentioned means and said spraying means for relative movement therebetween, driving means for effecting relative movement between said first-mentioned means and said spraying means and thereby effect relative traverse between the surface of the hat body to be sprayed and said spraying means, means for starting and stopping the discharge of said spraying means, and means operating in timed relation to the operation of said traversing means for controlling said discharge starting and stopping means.

11. An apparatus for applying a luring preparation onto a hat body comprising means for supporting a hat body, a liquid discharge device having valve control means, means providing a movable mounting for said device and valve control means, means operating upon said movable mounting for effecting a traversing movement thereof relative to the surface of the hat body to be treated whereby said discharge device and valve control means partake of motion of translation, and means operating in timed relation to the beginning and end of said traversing movement for controlling said valve means.

12. An apparatus for applying a luring preparation onto a hat body comprising means for supporting a hat body, a liquid discharge device having valve control means, means for effecting a relative traversing movement between the surface of the hat body to be treated and said discharge device, said traversing means comprising a movable mounting for said discharge device with said valve means and means for effecting movement thereof relative to said surface of the hat body, control means for said valve means and comprising operating connections to said valve means, said operating connections being operative during movement of said mounting with said discharge device and valve means.

13. An apparatus for applying a luring preparation, or the like, to a surface of a hat body comprising means for supporting and rotating a hat body, spraying means therefor, said spraying means comprising a liquid discharge device, means supporting the latter for movement about an axis to effect traverse thereof relative to the hat body, control means for said discharge device, and operating connections to said control means including an operating member positioned coaxially with said axis.

14. An apparatus for applying a luring preparation, or the like, to a surface of a hat body comprising means for supporting and rotating a 65 hat body, spraying means therefor, said spray-

ing means comprising a liquid discharge device, means supporting the latter for movement about an axis to effect traverse thereof relative to the hat body, said supporting means comprising a carrier having means for supporting it to swing about an axis and means relating said discharge means to said carrier for movement relative to the latter about an axis, means for controlling the movement of said carrier about its axis, and means for controlling movement of said discharge means relative to said carrier means.

15. An apparatus as claimed in claim 14 in which said discharge means is provided with control means for controlling its discharge, and 15 operative connections including actuating means respectively coaxial with said two axes for said control means.

16. An apparatus for applying a luring preparation, or the like, to a surface of a hat body, comprising means for supporting a hat body, spraying means, means mounting said first-mentioned means and said spraying means for relative movement therebetween sufficient to effect the desired relative traverse between the hat body surface to be sprayed and said spraying means, power-actuated driving means therefor, automatic means for halting the driving means and operating to effect halting in response to the completion of a certain relative traversing movement between said hat body supporting means and said spraying means, means for controlling the emission of the preparation from said spraying means, and means operating in timed relation to said halting means for actuating said controlling means.

17. An apparatus for applying a luring preparation, or the like, to a surface of a hat body, comprising means for supporting a hat body, spraying means, means mounting said first-mentioned means and said spraying means for relative movement therebetween sufficient to effect the desired relative traverse between the hat body surface to be sprayed and said spraying means and to bring them into or out of operative relation to each other, thereby to permit the replacement of a hat body when they are out of operative relation to each other, power-actuated driving means therefor, means for halting the driving means, means making said halting means operative automatically upon the completion of a certain relative traversing movement between said hat body supporting means and said spraying means, means for controlling the emission of the preparation from said spraying means, operating means for said controlling means, and operating connections between said operating means and said driving means for actuating said emission control means to prevent emission of the preparation when said hat-supporting means and said spraying means are out of operative relation to each other and for permitting emission of the preparation during movement of relative traverse between said spraying means and said hat-supporting means.

BURLING D. WELLS.
